UNITED STATES PATENT OFFICE.

NAPOLEON DU BRUL, OF CINCINNATI, OHIO.

DESIGN FOR A HAND-LEVER.

SPECIFICATION forming part of Design No. 23,581, dated August 21, 1894.

Application filed March 2, 1894. Serial No. 502,142. Term of patent 14 years.

To all whom it may concern:

Be it known that I, NAPOLEON DU BRUL, a citizen of the United States, residing at Cincinnati, in the county of Hamilton and State 5 of Ohio, have invented and produced a new and original Design for Hand-Levers, of which the following is a specification, reference being had to the accompanying drawing, which is a perspective view showing my design.

10 The leading feature of my design consists in a hand lever formed with an upwardly and outwardly extending arm having a surmounting ear-shaped handle at its upper end.

1 represents a hand lever formed at its lower end with an upwardly and outwardly extending arm 3. Surmounting the arm is an ear-shaped handle 4.

Having thus described my invention, the following is what I claim as new therein and desire to secure by Design Letters Patent:

15 The design for a hand lever substantially as herein shown and described.

NAPOLEON DU BRUL.
